R. V. NEWSHAM,
SELF OILING HANDLE FOR DIESTOCKS,
APPLICATION FILED MAY 31, 1919.

1,336,575.

Patented Apr. 13, 1920.

UNITED STATES PATENT OFFICE.

ROY V. NEWSHAM, OF SEATTLE, WASHINGTON.

SELF-OILING HANDLE FOR DIESTOCKS.

1,336,575.

Specification of Letters Patent. Patented Apr. 13, 1920.

Application filed May 31, 1919. Serial No. 300,805.

To all whom it may concern:

Be it known that I, ROY V. NEWSHAM, a citizen of the United States, and resident of the city of Seattle, county of King, State of Washington, have invented certain new and useful Improvements in Self-Oiling Handles for Diestocks, of which the following is a specification.

My invention relates to a handle designed 10 for application to such tools as thread cutting diestocks, the purpose of which is to provide means whereby oil may be automatically applied to the cutting portions of the die.

15 The object of my invention is to provide means for automatically oiling the cutting parts of such tools, and at the same time to provide a storage capacity for enough oil to last for a considerable time.

20 The features of my invention which I consider to be new and upon which I desire to obtain patent will be hereinafter set forth and then particularly defined in the claims.

In the accompanying drawings I have 25 shown the form of construction which I prefer to use.

Figure 1 shows a diestock having one of my handles applied thereto, the handle being shown in section.

30 Fig. 2 shows the same handle with the parts in the position which they would assume if reversed in position.

Fig. 3 shows an edge view of a diestock having my invention applied thereto, with 35 the central portion thereof in section.

Fig. 4 shows a transverse section through the handle upon the plane of the broken lines 4—4 of Fig. 1.

Fig. 5 is a longitudinal section through a 40 handle having a construction which differs only in detail from that shown in the other figures.

In the cutting of threads upon a pipe it is desirable that the dies be supplied with oil 45 steadily, and at all times when they are in use. To secure this, where the oil must be applied by hand by means of an ordinary oil can, is difficult, as the use of the oil as frequently as may be desired is improbable.

50 At the same time when used it is used in excess. I have, therefore, sought to provide means whereby one of the handles may be used as a reservoir for storing oil, and other means whereby this oil may be conducted to 55 the cutting parts of the die and be supplied in regular measured quantities to the die.

The means which I prefer to employ are those shown, and which will now be described.

The handle 1 may, in its general exterior 60 condition, resemble an ordinary handle. At its outer end it is provided with a removable cap or plug 2. Its inner end is threaded into the central body 3 of the diestock. In this latter respect it is similar to the ordinary handle. It is evident that if this handle be filled with oil it will constitute an oil storage reservoir of considerable capacity.

The inner end of this reservoir is provided 65 with means whereby the oil contained therein may be delivered to the die. Such means as herein shown consist of the pipe 30. For convenience of installation this pipe employs a section 31, which enters the inner end of the handle 1, and a section 32, which 70 is laterally bent, so that its inner discharge end terminates closely alongside of the inner face of the die 33. For convenience of installation I also employ a union coupling, 75 as is indicated at 34.

80 Within the inner end of the handle 1 is placed a plug 4, which is provided with a central bore, into one end of which the section 31 of the oil delivering pipe is screwed. In the other end of the plug 4 is a bore 85 which is connected with the bore into which the pipe 31 is screwed. This forms a cylinder which cooperates with a piston for the forcing out of a measured quantity of oil. This plug 4 is secured in place by having the 90 end faces of the handle 1 engaging with ledges or flanges 40 which extend about the same. A non-leaking joint is secured by interposing a washer, as 41, of any soft material between the end of the plug 4 and the 95 bottom of the bore, into which the handle 1 is inserted.

Within the oil storage chamber is placed a 100 bar 5, which is adapted by its weight, to act as the force for operating the pump. To one 105 end of this is secured an extension 50, which is of a reduced size to enter the bore 42, which is formed in the inner end of the plug 4. The bar 5 is preferably made of a triangular cross section, as is shown in Fig. 4, 110 so that it may move freely within the handle, and the oil may flow from one side thereof to the other, freely. At the same time this bar may thus be held fairly well centered within the handle.

115 The plug 2, which closes the outer end of the handle 1, is provided with a central axial

bore, into which is threaded stem 60 of a regulating button or cylinder 6. The outer end of the plug 2 is bored or recessed to receive the button 6 and the inner end of the stem 60 is provided with a ring or stop 61, which will prevent its being screwed outward farther than desired, and will also furnish an enlarged head for engagement with the outer end of the bar 5.

10 By adjusting the button 6 in or out, which may be done by turning it, the length of stroke of the bar 5 may be controlled. By screwing this in a sufficient distance, the removal of the inner end of the reduced stem 50 from the bore 42 formed in the plug, may be prevented. In this event the action of the device for pumping oil is neutralized. This may be done when it is desired to put the oil supply device out of use, as when the 20 tool is to be laid away for any length of time. By properly adjusting the button 6, the free flow of oil into the cylinder 42 may also be controlled to a certain extent.

In the form of device shown in Fig. 5, the bar 5 occupies the inner portion of the handle 1 and the threaded stem 60 extends inward a much greater length than in the construction shown in Figs. 1 and 2. The construction shown in Figs. 1 and 2 is preferred, as the piston bar 5 occupies the outer portion of the handle and the oil does not have to flow past the same in order to reach the pump cylinder, that is, the bore in the plug member 4.

35 In operation, the bar 5 will be reciprocated if the handle bar is brought to a vertical position. It will thus be moved toward the outer end of the handle when this bar is at the lower side of the stock, and 40 will be moved inward to discharge oil when this handle is placed upward from the stock. The oil discharge will be deposited directly upon the surface of the pipe and upon the side face of the die. In either event it will 45 be at the point where it is most needed. In consequence, a lesser amount of oil will be required and a more thorough oiling of the threads being cut will be secured.

What I claim as my invention is:

50 1. An automatic oiling device for die stocks and like tools, comprising a hollow handle adapted to serve as an oil storage reservoir, a closure for the inner end of this handle having an oil pump cylinder, a delivery pipe connecting said cylinder with the point where the oil is to be used and a weight free to move by gravity within said handle and having a tip forming a piston

adapted to enter the pump cylinder to expel its contents, and means for adjustably controlling the length of stroke of the pump piston.

2. An automatic oiling device for die stocks and like tools, comprising a hollow handle adapted to serve as an oil storage reservoir, a closure for the inner end of this handle having an oil pump cylinder, a delivery pipe connecting said cylinder with the point where the oil is to be used and a weight free to move by gravity within said handle and having a tip forming a piston adapted to enter the pump cylinder to expel its contents, and an adjustable rod entering the outer end of the handle and adapted to engage the weight to control and limit its stroke.

3. An automatic oiling device for die stocks and like tools comprising a hollow handle adapted to serve as an oil storage reservoir, a closure for the inner end of this handle having an oil pump cylinder, a delivery pipe connecting said cylinder with the point where the oil is to be used and a weight free to move by gravity within said handle and having a tip forming a piston adapted to enter the pump cylinder to expel its contents, a plug screwing into the outer end of the handle and having its outer end recessed, an adjusting bolt threaded into and passing through said plug and adapted to engage the outer end of the pump operating weight, said bolt having a head which may enter the recess in said plug.

4. In an automatic oiling device for die stocks and like tools, the combination with a stock having a handle receiving socket provided with a base opening, a packing washer seated within the socket, a hollow handle adapted to serve as an oil storage reservoir and having its inner end threaded into said socket, a closure for this end of the handle having an oil pump cylinder, and provided with a rounded outer end and a peripheral flange engageable by the inner end of the handle to press said rounded end against said washer to prevent leakage through said socket opening, a delivery pipe leading from the pump cylinder to a point where the oil is to be used and a weight free to move by gravity within said handle having a tip forming a piston adapted to enter the pump piston to expel its contents.

Signed at Seattle, Washington, this 21st day of May, 1919.

ROY V. NEWSHAM.
